UNITED STATES PATENT OFFICE.

JOSEPH V. DESMARAIS, OF NEW BEDFORD, MASSACHUSETTS.

ATTACHMENT FOR LOOMS.

1,244,842.

Specification of Letters Patent. Patented Oct. 30, 1917.

Application filed October 24, 1916. Serial No. 127,459.

To all whom it may concern:

Be it known that I, JOSEPH V. DESMARAIS, a citizen of the United States, and resident of New Bedford, Bristol county, State 5 of Massachusetts, have invented certain new and useful Improvements in Attachments for Looms, of which the following is a specification.

This invention relates to looms and more 10 particularly to an attachment therefor. The objects of the invention are to provide a device which will prevent the loom operator from putting a shuttle in a box when no shuttle should be in the same; to provide 15 such a device which is easily attachable to a loom, has very few parts and is efficient and dependable in action.

The single figure shows a perspective view 20 of a portion of a loom with the attachment applied thereto.

One of the side frames 10 of the loom has pivotally mounted thereon as at 11 one of the arms 12 of the lay 13. The lay may be of the usual construction having at one end 25 a single shuttle box 14 and at the other end a plurality of shuttle boxes 15. At the rear of the loom a shaft 16 is rotatably mounted in the side frame and this shaft may have connections for operating the picker sticks. 30 Fixed to this shaft adjacent the side frame 10 is a cam 17 which is adapted to operate my attachment. This attachment includes a gate which is adapted to be moved to cover and uncover the mouth of the box 14. As 35 clearly shown in the drawing, a lever 18 is pivotally mounted at 19 on the side frame 10 and carries a roller 20 which is adapted to coöperate with the periphery of the cam 17. A link 21 is pivotally connected at one 40 end to the end 22 of the lever 18 and at its other end to the lower end of a vertically arranged rod 23. This rod is slid- 45 ingly mounted and guided by any suitable means such as the bracket 24 and carries at its upper end a gate 25 which is adapted to cover the entrance to the box 14. While I have shown this gate 25 as a plate, it is obvious that it may take any other suitable form.

50 In assembling the machine, the cam 17 is so positioned or attached to the shaft 16 that when a shuttle is not and should not be present in the box 14 the gate 25 will obstruct the mouth thereto. In the opera- 55 tion of the machine as the shaft 16 rotates

and the picker sticks are operated, the shuttle will be thrown from a box on one side of the lay to a box on the other side. By means of the cam 17 the lever 18 will be oscillated on its pivot 19 and through the link 21 will reciprocate the rod 23 and also the gate 25 to alternately cover and uncover the mouth of the box 14. As the timing of the movements of these parts is such that the gate 25 is in front of the box 14 when a shuttle should not be present therein it will be obvious that if for any reason the loom is stopped an operator cannot insert a shuttle in the said box 14 when one should not be present therein.

70 While I have mentioned the shaft 16 as being connected to operate the picker sticks, it is obvious that my attachment may be operated from any rotatable member of the loom which rotates in timed relation with the movement of the shuttle across the lay. The only requirement is that the gate 25 be operated so that it will be open when a shuttle is properly in the box 14 and will be closed when a shuttle should not be present therein. It is obvious that the details of the means for actuating the gate may be greatly varied without departing from the spirit of the invention.

Having thus described the invention what 85 is claimed and desired to be secured by Letters Patent is:

1. In a loom having a single box at one end of the lay, means for obstructing the entrance to said box when a shuttle should 90 be in a box at the other end of the lay to thereby prevent the operator from inserting a shuttle in said single box.

2. In a loom, a movable member arranged 95 in front of the entrance to a box at one end of the lay, and means to automatically actuate said member to obstruct the said entrance when the box should be empty and to move it away from said entrance when a shuttle should be in said box.

3. In a loom having a single box at one end of the lay, a gate movable into the path of the shuttle to and from said box, and means automatically operated by the loom for moving said gate to obstruct said path 105 when the said box should be empty.

4. In a loom having a single box at one end of the lay, a movable gate arranged to 110 obstruct the entrance to said box when the box should be empty and means automati-

cally operated by the loom for moving said gate away from said entrance when a shuttle should be in said box.

5. In a loom having a single box at one end of the lay, a movable gate arranged to obstruct the entrance to said box when the box should be empty and cam means operated by the loom for moving said gate away from said entrance when a shuttle should be in said box.

6. In a loom having a single box at one end of the lay, a movable gate arranged to obstruct the entrance to said box when the box should be empty and means rotating in timed relation with the picker stick operat-

ing means for moving said gate away from said entrance when a shuttle should be in said box.

7. In a loom having a box at one end of the lay and a plurality of boxes at the other end, a gate arranged to move across the mouth of said first mentioned box, a member rotating in timed relation with the movement of the shuttle across the lay and means operated by said member to move said gate to obstruct the mouth of said box when no shuttle should be therein.

In testimony whereof I affix my signature.

JOSEPH V. DESMARAIS.
